UNITED STATES PATENT OFFICE.

JAMES O. MCINTOSH, OF CALIENTE, NEVADA.

WATER-RAISING WHEEL.

1,078,103.

Specification of Letters Patent. Patented Nov. 11, 1913.

Application filed April 3, 1912, Serial No. 688,150. Renewed April 1, 1913. Serial No. 758,260.

To all whom it may concern:

Be it known that I, JAMES O. MCINTOSH, a citizen of the United States, residing at Caliente, in the county of Lincoln and State 5 of Nevada, have invented new and useful Improvements in Water-Raising Wheels, of which the following is a specification.

This invention relates to improvements in water raising devices, and it is an object of 10 the invention to provide a mechanism by which water may be raised from a moving stream by power derived from the motion of the stream itself.

It is also an object of the invention to suspend a water wheel so that it will engage and be moved by the moving water of the river or other stream, and to provide spiral water pipes adapted to take water from the river as they are turned by the said wheel 20 and to deliver the same into piping or troughs for distribution.

In the accompanying drawing forming a part of this specification, Figure 1 is a side elevation of the improved water wheel mechanism as mounted upon the bank of a stream. Fig. 2 is an enlarged end elevation of the mechanism, looking at one side of the water wheel, parts being broken away to show the water lifting tubes. Fig. 3 is a 30 side elevation of the stream engaging portion of the water wheel mechanism, showing the same upon an enlarged scale. Fig. 4 is an enlarged fragmentary sectional view through the central portion of one of the 35 spiral water taking pipes. Fig. 5 is a side elevation of the framing upon which the wheel mechanism is supported. Fig. 6 is a horizontal sectional view through the bearing which supports the discharge pipe of the 40 mechanism. Fig. 7 is a transverse sectional view through the pipe and the supporting collar therefor at said bearing.

The details and features of said invention will now be more particularly described, 45 reference being had to the said drawing in which—

10 indicates a water wheel and 11 a water raising section thereof. The wheel sections are supported upon suitable shafting. The 50 portion of the shaft which extends through the wheel section 10 is preferably an ordinary

solid shaft as 12 journaled at its outer and inner ends in supporting bearings 13 and 14 which are carried by the lower ends of supporting links 15 and 16. The upper ends of said links are connected by means of short cables with a supporting arm or beam 17. The said beam 17 projects in an approximately horizontal position from a derrick standard 18 which is mounted upon 55 the adjacent bank of the stream. The lower end of said derrick frame is preferably formed with a rocking or hinge bearing at 19 so that the upper end of the frame may be moved inwardly and outwardly to a 60 slight extent in adjusting the height of the wheel from the stream.

Mounted adjacent to the derrick frame 18 is a similar frame 20, preferably arranged above the said frame 18 and generally in alignment therewith. In the upper portion of the said frame 20 are pulleys 21 and 22 over which bracing cables 23 and 24 pass, their outer ends being secured to the arm 17 by any suitable fastenings while 70 their inner ends extend to a point on the shore or bank where they are secured by means of stakes 25 or other suitable means. The upper end of the smaller derrick frame 18 is preferably provided with a brace 26, 80 which is usually connected with the said frame by a hinge or pivotal joint and the lower end of said brace is caused to rest against a stake 27 driven into the bank.

The inner section 11 of the water wheel is 85 provided with a hollow shaft forming a water discharge pipe 28. The outer end of said shaft is closed and is firmly connected with a solid shaft 12 so as to be movably supported therewith. The inner end of said 90 pipe extends to a suitable point over the bank of the river or stream and is generally left open and caused to discharge into a trough 29 mounted upon the bank.

The discharge pipe 28 forming the axle 95 of the wheel section 11 is movably supported in a bearing collar 30. The said collar 30 has trunnions 31 projecting from the sides thereof and engaging slide bearings 32 which are movably mounted in standards 100 33 resting upon the bank of the stream. A screw 34 is mounted in the cross head 35 of

said standards 33 and the lower end of said screw has an enlarged head 36 which extends into a bearing 37 formed in the upper portion of the collar 30. A screw cap 38 holds the head of the said bolt in its bearing. It will be understood that by turning the said screw 34, the collar 30 may be raised or lowered for adjusting the height of the discharge pipe 28.

10 The wheel section 10 is preferably made up of circular frames 39 which are braced and supported upon radial bars which extend to the center of the wheel and are mounted upon the shaft 12 so as to be capable of turning the same. Between the peripheral portions of the frame 39, paddles 40 are arranged and set at a suitable angle as shown in Fig. 2 to receive the impact of the water in the stream so that the flow of the stream will turn the wheel. The wheel section 11 is formed with similar circular frames 41 which are also provided with paddles 42 like the paddles 40. The central portion of the said wheel section 11 is however, provided with water taking spiral shaped tubes 43, there being preferably a series of said tubes mounted side by side and arranged so that their inner ends extend to the discharge pipe 28. The inner end of each of said spiral tubes is formed as shown in Fig. 4 so as to cover an opening 44 made in the discharge pipe 28. The outer ends of the spiral tubes are open and usually inclined as shown at 45 facilitating the taking of water by the tubes when they are turned with the current of the stream. The action of the tubes in taking water and forcing it to the central discharge pipe 28 is similar to the action of the Archimedean screw. The said spiral tubes however are arranged in parallel planes to each other as clearly shown in Figs. 1 and 3 and are set so that not all of the tubes take water at the same time. In fact they are usually arranged so as to take water successively at different points around the periphery of the wheel so that a continuous stream of water may be forced into and through the discharge pipe.

50 The spiral tubes may be made of any desired shape in cross section but they are preferably made rectangular in cross section as clearly shown in Fig. 3. Inasmuch as air will be entrapped in the tubes between each dipping of the open end thereof into the water, the said tubes are preferably provided with air vents 46. A portion of each vent tube extends parallel with the spiral direction of the body portion of the tube itself and the outer end of the said tube is open for 55 permitting the air to escape while the inner end is turned inwardly approximately at right angles to the body portion thereof and secured to the spiral tubing at a point opposite the opening through which the water en-

ters the discharge pipe from said tube. The preferable position of the inner vent pipe with respect to its spiral tube is clearly illustrated in Fig. 4 of the drawing. It is also preferable to employ other vent pipes as 47 located near the outer coil of the central pipe 70 as shown in Fig. 2. It will be observed that these vent pipes also enter the spiral tube at right angles thereto so that there is no tendency for the water in the spiral tube to run out the vent pipes. The said vent pipes 75 are found to permit the escape of the air entrapped into the tubes so that the discharge of water from the series of spiral tubes in the discharge pipe forms a continuous outflowing stream. The inner ends of 80 the spiral tubes at the point where they meet the discharge pipe are preferably curved to one side as indicated at 48, thus facilitating the easy flowing of the water from the said tubes into the discharge pipe. 85

A wheel of this construction is especially well adapted for use in streams having a fair degree of flow and makes it possible to utilize the force of the current with a device which is entirely mounted upon the land. The 90 spirals are so arranged with respect to the vent pipes that the water is always resting upon the closed side of the spiral instead of upon the side which is tapped by the vent pipe. 95

It will be understood of course that the edges of the derricks and the guy ropes or braces will hold the wheel in proper relation to the surface of the stream. The device where it is used in tide waters will also require some adjustment because of the differences of the tides. For holding the wheel against the action of the current of the stream one or more guy ropes or stay lines 50 may be used and secured to arms 51, extending from the shaft of the wheel outwardly between its sections to points beyond its periphery. The outer ends of such ropes or lines are secured in any desired manner upon the bank of the stream. 100 105 110

What I claim is:

1. A water wheel for streams, comprising a paddle member a tube bearing member, means for supporting the same, spiral tubes mounted in said tube bearing member having open outer ends adapted to scoop up water from the stream, and vent pipes apertured at right angles in one turn of said spiral tubes, passing to and extending along the next outer spiral turn and having a vent opening on its outer end, opening in the direction of progression adapted to release air entrapped in said spiral tubes. 115 120 125

2. A water wheel construction, comprising paddle wheels and water taking tubes carried thereby, a hollow shaft adapted to receive water from the said tubes, a laterally adjustable arm supported at one end in a

pivoted frame, a stationary frame provided with means adapted to support the other end of said arm, links connecting the shaft of the paddle wheel to said arm, and means for moving said arm in the direction of its axis to permit adjustment of the wheel to variations of water level.

In witness that I claim the foregoing I have hereunto subscribed my name this 26th day of March, 1912.

JAMES O. McINTOSH.
